Patented Nov. 18, 1975

237,706

CLOCK FACE

Ronald Reginald Burgess, Phoenix, Michael Garm Coleman, Tempe, Lawrence Ames Grenon, Phoenix, and Israel Arnold Lesk, Scottsdale, Ariz., assignors to Motorola, Inc., Chicago, Ill.

Continuation-in-part of abandoned design applications Ser. No. 120,382, Ser. No. 120,383, and Ser. No. 120,384, all Mar. 2, 1971. This application Jan. 22, 1973, Ser. No. 325,384

Term of patent 14 years

Int. Cl. D10—07

U.S. Cl. D10—123

Fig. 1

Fig. 2

Fig. 3

Fig. 4

Fig. 5

FIG. 1 is a plan view of a clock face embodying our new design;

FIG. 2 is a plan view showing a modified form of our design;

FIG. 3 is a plan view showing another modified form of our design;

FIG. 4 is a plan view showing still another modified form of our new design; and

FIG. 5 is a plan view showing a further modified form of our new design.

The clock face is of conventional thickness.

This is a continuation-in-part of copending applications Ser. Nos. D. 120,382, D. 120,383, and D. 120,384, all filed Mar. 2, 1971 and now abandoned.

We claim:

The ornamental design for a clock face, as shown and described.
